HOLDER FOR COCKTAIL MIXERS

Richard I. Sanger, New York, N. Y.

Application April 5, 1954, Serial No. 29,870

Term of patent 7 years

(Cl. D2—3)

Fig. 1

Fig. 2

Fig. 1 is a front perspective view of a holder for cocktail mixers showing my new design; and

Fig. 2 is a rear perspective view thereof.

The portions shown in broken lines are for the purpose of illustration.

I claim:

The ornamental design for a holder for cocktail mixers, as shown and described.

No references cited.
